[57] CLAIM

The ornamental design for a mounting plate for electrically operated exit device strike, as shown and described.

DESCRIPTION

FIG. 1 is a front perspective view of the mounting plate for electrically operated exit device strike embodying my design;

FIG. 2 is a front elevational view of the mounting plate for electrically operated exit device strike as shown in FIG. 1;

FIG. 3 is a rear perspective view of the mounting plate for electrically operated exit device strike as shown in FIG. 1;

FIG. 4 is an end elevational view of the mounting plate for electrically operated exit device strike as shown in FIG. 1, the opposite end elevational view being identical;

FIG. 5 is a rear elevational view of the mounting plate for electrically operated exit device strike as shown in FIG. 1;

FIG. 6 is a side elevational view of the mounting plate for electrically operated exit device strike; and,

FIG. 7 is an opposite side elevational view of the mounting plate for electrically operated exit device strike as shown in FIG. 1.

FIG. 1

FIG. 2

FIG. 3

FIG. 4

FIG. 5

FIG. 6

FIG. 7
